FASTENER-APPLYING IMPLEMENT

John F. Cavanagh, Providence, R. I., assignor to
 Boston Wire Stitcher Company, Warwick, R. I.,
 a corporation of Maine

Application July 7, 1937, Serial No. 152,339

9 Claims. (Cl. 1—3)

This invention relates to fastener-applying implements of the type in which the fasteners are supplied to the magazine at its forward end, and more particularly to an automatically-operated 5 retainer for preventing ejection of the fasteners when the magazine is opened.

In one known type of fastener-applying implement a refill stick or charge of fasteners is supplied to the magazine at its forward end by sliding 10 it onto a core therein. In this type of implement a closure or gate hinged to the forward end of the magazine is rockable to open the end thereof. A stick of preformed fasteners, held together by adhesive, is then slid rearwardly into 15 the magazine against the force of a spring-pressed pusher. In such implements a spring-operated pawl is sometimes provided for engaging the stick of fasteners when the gate is opened and adapted to be rocked to release the fasteners when the gate is closed. The pawl thus opposes 20 the action of the pusher when the gate is open to prevent ejection of the fasteners from the magazine. Although this type of retainer is quite satisfactory in use its point or beak is subject to considerable abrasive action and eventually becomes worn down or rounded over so that it will 25 not properly hold the fasteners. Consequently, any fasteners remaining in the magazine when the gate is opened may be ejected by the pusher.

One of the objects of the present invention is to 30 provide an implement of the type indicated having a novel form of fastener-retainer which is not rendered inoperative by wear.

Another object of the invention is to provide 35 a retainer of the type indicated comprising a member adapted to be moved bodily forward into wedging engagement with the fasteners and moved rearwardly out of wedging engagement to release the fasteners.

Another object of the invention is to provide a 40 retainer of the type indicated in the form of a wheel rotatably and bodily movable for wedging action between the fasteners and a relatively fixed abutment.

Still another object of the invention is to provide 45 a retainer of the type indicated which is of simple and compact construction, efficient and positive in operation and adapted for use over long periods of time without repair or replacement.

Further objects of the improvement are set forth in the following specification which describes a preferred embodiment of the invention, by way of example, as illustrated by the accompanying drawings. In the drawings:

Fig. 1 is a side elevation of a fastener-applying implement incorporating the present invention;

Fig. 2 is a longitudinal sectional view of the forward end of the magazine-arm of the implement showing the retainer held by the closure 5 free from engagement with the fasteners;

Fig. 3 is a view similar to Fig. 2 showing the closure rocked to its open position and the retainer in wedging engagement between the fasteners and an abutment on the magazine-arm; 10

Fig. 4 is a front elevational view of the implement showing the parts in the relationship illustrated in Fig. 3;

Fig. 5 is a detailed sectional view of the retainer and magazine-arm showing the retainer wedged 15 between the abutment on the arm and the pusher for the fasteners; and

Fig. 6 is a detailed perspective view of the parts of the retainer in disassembled relationship.

The retaining means constituting the subject- 20 matter of the present invention is illustrated in the accompanying drawings as applied to an implement of the type shown and described in a pending application for United States Letters Patent, Serial No. 59,256, filed January 15, 1936. 25 Such implements are employed for applying U-shaped staples to the work but it is to be understood that the invention may be used with other types of implements or with similar implements for applying other forms of fasteners. 30

The stapling implement as herein illustrated 35 comprises a base 2 of usual construction having a clincher-anvil 3 at its forward end and upstanding spaced ears 4 at its rearward end. An arm 5 in the form of a magazine is rockably mounted 40 on a pivot-pin 6 extending between the spaced ears 4 and through a suitable bearing 7 on the arm. The arm 5 is yieldingly held in raised position as illustrated in Fig. 1 by means of a spring-pressed button 8 on the base 2 which yields to 45 permit the arm to be rocked about the pivot-pin 6. The magazine 5 is comprised of a U-shaped member 9 provided with a longitudinally-extending inner support or trough-shaped core 10, see Fig. 4. The core 10 is adapted to support 50 staples 5 straddled across its top and held in place thereon by the folded-over sides of the U-shaped member 9. Secured to the arm 5 adjacent its forward end is a U-shaped bracket or standard 55 forming spaced stanchions 16 and 17 connected at their rearward edges by a web 18. Flanges 19 and 20 integral with the stanchions 16 and 17 extend outwardly and downwardly to overlie the sides of the U-shaped member 9 and are fixedly secured thereto as by welding or the 55

like, see Fig. 4. The stanchions 16 and 17 project upwardly beyond the web 18 and are provided with aligned, vertically-extending slots 21 adjacent their upper edges.

5 The forward end of the magazine-arm 5 may be provided with any suitable closure and, as herein illustrated, the closure is in the form of a U-shaped housing 25 which supports the staple-applying mechanism, thus forming a self-contained unit. The housing 25 is pivotally mounted 10 on the stanchions 16 and 17 by means of a pin 26 extending through the aligned slots 21 in the stanchions with its ends riveted or otherwise secured to the opposite side walls 27 and 28 of the 15 housing. When the housing 25 is in closed position, as illustrated in Fig. 2, its front wall 29 cooperates with the end of the magazine-arm 5 to form a throat 30 through which the staples are driven. The lower edges of the sides 27 and 28 20 of the housing 25 are formed with notches 31 which engage with lugs 32 on the flanges 19 and 20 of the stanchions 16 and 17 to releasably latch the stapling unit in closed position. The notches 31 are yieldingly held in latched engagement with 25 the lugs 32 by a spring 33 connected to the pivot-pin 26 and anchored at its lower end to a lug 34 struck up from the web 18. The housing 25 may be moved vertically with respect to the arm 5 30 against the action of the spring 33 to release the notches 31 from latched engagement with the lugs 32 whereby to permit the housing to be swung to open position as illustrated in Fig. 3, the slots 21 permitting the pin 26 to move upwardly therein during the relative movement of 35 the housing and arm.

The staple-applying mechanism comprises a hollow, rectangular plunger 40 mounted for reciprocation in the housing 25 and carrying a staple-driver 41 on its forward side in alignment 40 with the anvil 3 on the base 2. The plunger 40 is guided at the front and sides by the front wall 29 and side walls 27 and 28 of the housing 25 and at its rear by a backing plate 42. The backing plate 42 is supported at its upper end by inwardly-directed flanges 43 on the side walls 27 45 and 28 of the housing 25. The backing plate is supported at the bottom by a pin 44 extending through a bearing 45 in the lower forwardly bent end of the plate, the ends of the pin being secured to the side walls 27 and 28 of the housing 50 25. The plunger 40 and staple-driver 41 are normally held in raised position as illustrated in Fig. 2 by a helical compression spring 46 positioned in the hollow of the plunger and acting 55 between a knob 47 secured to the top of the plunger and the pin 44. As shown most clearly in Fig. 2, the staple-driver 41 is adapted to be reciprocated in the throat 30 to drive the staples into the work with its descent limited by the engagement of a lug 48 extending rearwardly from the plunger 40 with the end of a slot 49 in the 60 backing plate 42.

The staples *s* supported on the core 10 are slid forwardly in the magazine-arm 5 and fed successively into the throat 30 by means of a staple-pusher 50. The staple-pusher 50 is of inverted U-shape to adapt it to ride on the core 10 at the rear of the staples and to fit in the space between the core and channel member 9. The pusher 50 70 is urged forwardly in the magazine by means of an elastic cord 51 connected to it at one end and looped around a suitable post 52 with its opposite end connected to the arm 5. An inclined cam-face 53 is provided at the forward end of the pusher 50 adapted to be engaged by the end 75

of the driver 41 when the magazine is empty to move the pusher rearwardly therein. Although the cam-face 53 may take other forms, as illustrated in Figs. 2 and 4 it is constituted by an ear 54 struck up from the top of the pusher 50, the forward edge of the ear being ground or otherwise beveled to incline it rearwardly from the front of the pusher.

In accordance with the present invention a novel form of staple-retainer is provided comprising an element movable longitudinally of the arm 5 into binding engagement with the staples *s* to dog the latter when the housing 25 is opened and movable in the opposite direction to release the staples when the housing is closed. Although 10 the movable element may take other forms, as herein illustrated it comprises a wheel 60 having a serrated periphery 61. The wheel 60 is mounted to rotate and slide bodily in a U-shaped frame 62 having spaced wings 63 and 64 connected at 15 one end by a web 65. The wings 63 and 64 of the frame 62 are provided with aligned holes 66 and aligned slots 67 inclined downwardly therefrom rearwardly of the web 65, see Fig. 6. The wheel 60 is supported between the wings 63 and 20 25 64 of the frame 62 by means of a pin 68 fast in an axial bore 69 in the wheel with its ends projecting into the inclined slots 67. The wheel 60 is thus free to rotate and move bodily with the pin sliding in the inclined slots 67, the spaced 30 wings 63 and 64 holding the wheel laterally positioned in the frame. The frame 62 is rockably mounted on a fixed pin 70 extending between the stanchions 16 and 17 above the core 10 and through the aligned holes 66 in the wings 63 and 35 64. With the parts of the retainer assembled on the arm 5 as illustrated in Figs. 2 and 4 the wheel 60 is positioned at the rear of the pin 70 while the web 65 of the U-shaped frame 62 is positioned forwardly of the pin to adapt it to be 40 engaged by the backing plate 42 in the housing 25.

A spring 71 is coiled about the pin 70 at one side of the frame 62 with one end in hooked engagement with the frame and the opposite end bearing against the pin 26 which acts as an abutment to cause the frame to be yieldingly rocked in a counterclockwise direction as viewed in Fig. 3. The edges of the inclined slots 67 which engage the projecting ends of the pin 68 act as cams tending to move the wheel 60 bodily into and out of wedging engagement between the fasteners *s* and the pin 70. For example, when the frame 62 is rocked in a counterclockwise direction by the spring 71 the rearward edges of the slots 67 bear 55 against the ends of the pin 68 to move the wheel 60 forwardly of the arm 5 to dog it against the staples while the opposite edges of the inclined slots cam the wheel rearwardly to release the staples when the frame is rocked in a clockwise 60 direction. Due to the loose connection of the wheel 60 with the frame 62 the wheel is adapted to automatically adjust itself between the staples *s* and the pin 70, which latter acts as an abutment, and the serrated periphery 61 positively 65 grips the staples *s* and pin 70. One embodiment of the invention having been described in detail the mode of operation of the device will be next explained.

To load the magazine 5 with a refill of staples 70 *s* the housing 25 which constitutes the closure for the forward end of the magazine is first lifted to release the notches 31 from latched engagement with the lugs 32 and then rocked on its pivot 26 75 to open position illustrated in Fig. 3. This rock-

ing movement of the housing 25 releases the backing plate 42 from engagement with the web 65 on the frame 62 and the spring 71, acting between the abutment 26 and the frame 62, immediately rocks the latter from the position shown in Fig. 2 to that shown in Fig. 3. The rocking movement of the frame 62 moves the wheel 60 downwardly and the inclined edges of the slots 67 act as cams or wedges to move the wheel forwardly. If there are any considerable number of staples in the magazine the edge 61 of the wheel 60 is wedged between the staples and the abutment pin 70 as shown in Fig. 3. If there are only a few or no staples in the magazine the wheel wedges between the top of the pusher 50 and the abutment pin 70 as illustrated in Fig. 5. The staples and pusher are thus held against ejection from the magazine under the action of the resilient cord 51. Due to the loose mounting 20 of the pin 68 in the frame 62 the wheel 60 is permitted to adjust itself to positively contact its serrated edge 61 with the staples s and the abutment pin 70. Moreover, the force of the pusher 50 urging the staples forwardly in the magazine 25 tends to rotate the wheel 60 and increase its binding engagement with the abutment pin 70.

After the magazine has been opened in the manner as above explained a refill stick of staples s may be inserted thereinto by sliding it onto 30 the core 10 against the action of the pusher 50. The rearward movement of the staple stick in the magazine causes the wheel 60 to be moved rearwardly in the same direction to release its wedging engagement, the wheel being rotated on 35 the staples as the stick is inserted. When the stick is released the combined action of the spring 71 and the forward movement of the stick by the pusher 50 immediately cause the wheel 60 to be moved forwardly into wedging engagement between the staples s and pin 70. After the magazine 40 has been fully loaded the housing 25 is rocked on its pivot 26 and latched in closed position as illustrated in Fig. 1 by engaging the notches 31 with the lugs 32. During the last increment of movement of the housing 25 to its 45 closed position the backing plate 42 engages the web 65 of the frame 62 and rocks the latter in a clockwise direction against the action of the spring 71 to the position shown in Fig. 2. The bottom edges of the inclined slots 67 then act to 50 cam the wheel 60 rearwardly and out of wedging engagement to release the staples s. The arrangement of the parts is preferably such that the ends of the pin 68 bottom in the lower ends of 55 the slots 67 as the frame 62 is rocked by the backing plate 42 so that the wheel 60 is lifted out of engagement with the staples s as illustrated in Fig. 2.

The pusher 50, acted upon by the resilient cord 51, moves the staples s forwardly in the magazine 5 to position the foremost staple of the stick in the throat 30 beneath the drive 41. The staple in the throat 30 may then be driven into the work by depressing the plunger 40 against the action of the spring 46 which causes the driver 41 to be moved downwardly through the throat. When released, the plunger 40 is returned to the position illustrated in Fig. 2 by the spring 46 which positions the end of the driver 41 above 60 the staples so that the next succeeding staple in the stick may be advanced by the pusher 50 to a position beneath the end of the driver. The operation of driving the staples may thus be continued until the supply in the magazine is entirely exhausted. When the supply of staples s is

exhausted, or if a staple becomes jammed in the throat 30, the closure 25 is rocked to its open position illustrated in Fig. 3 to again refill the magazine or to release the jammed staple as the case may be. It will be noted that each time the closure 25 for the magazine 5 is rocked to open position the wheel 60 is automatically moved into wedging engagement between the staples s and the abutment pin 70 and thus the wheel 60 is rotated from time to time so that different portions of its serrated edge 61 engage the staples s and pin 70 whereof to distribute the wear over the entire periphery of the wheel. 5

It will be observed from the foregoing that the present invention provides a novel form of staple-retainer adapted to be automatically carried into binding engagement with a stationary abutment and the staples in the magazine. It will also be observed that the present form of retainer is of simple and compact construction, adapted to be 10 used on standard types of machines, being positive in its operation to dog the staples to prevent their accidental ejection from the magazine of the device. 15

While the improved device is herein described 20 and illustrated as embodied in a preferred form of construction, it is to be understood that various modifications may be made in the structure and arrangement of its parts without departing from the spirit or scope of the invention. For 25 instance, the movable wedging member may have other forms than a wheel, as herein illustrated, and the wedging member may be arranged in other forms of supports than the cage frame, herein shown and described, to adapt the wedging 30 element to be moved into and out of binding engagement with the staples. Therefore, without limiting myself in this respect, I claim: 35

1. In a device of the type indicated, a magazine for holding a supply of fasteners, a movable closure for the magazine, means for advancing the fasteners in the magazine, a member mounted to rotate on a displaceable axis adjacent the end of the magazine, and means for displacing the axis of the member to cause it to engage the 40 fasteners to prevent their ejection from the magazine when the closure is opened. 45

2. In a device of the type indicated, a magazine for holding a supply of fasteners, a movable closure for the magazine, means for advancing the fasteners in the magazine, a member mounted to rotate and move bodily above the fasteners adjacent the end of the magazine, and means for bodily moving said member to engage it with the fasteners to prevent their ejection from the 50 magazine when the closure is opened. 55

3. In a device of the type indicated, a magazine for holding a supply of fasteners, an abutment adjacent the end of the magazine, a movable closure at the end of the magazine, means 60 for advancing the fasteners in the magazine, a wheel having serrations on its periphery, means for mounting the wheel adjacent the end of the magazine to adapt it to move into wedging engagement between the abutment and the fasteners, and means actuated by the closing of the closure for moving the wheel to release the fasteners. 65

4. In a device of the type indicated, a magazine for holding a supply of fasteners, an abutment in the magazine above the fasteners, a movable closure at the end of the magazine, means for advancing fasteners in the magazine, a retainer bodily movable longitudinally of the magazine, and means for yieldingly urging the re- 70 75

- tainer into wedging engagement between the fasteners and the abutment when the closure is opened, said retainer being actuated by the closing of the closure to release the fasteners.
5. In a device of the type indicated, a magazine for holding a supply of fasteners, an abutment adjacent the end of the magazine, a movable closure for the magazine, means for advancing the fasteners in the magazine, a frame pivotally mounted adjacent the end of the magazine, a retainer bodily movable on the frame, and yielding means for rocking the frame to wedge the retainer between the abutment and fasteners, said frame being rocked by the closing movement of the closure to release the fasteners. 5
10. 6. In a stapling or wire-stitching machine, a magazine for holding a supply of staples, a movable closure at the end of the magazine, means for advancing the staples in the magazine, a pin extending transversely of the magazine above the staples, a frame pivotally mounted on the pin and having inclined slots, a staple-retainer on the frame having trunnions extending through said slots, and a spring for rocking the frame to wedge the staple-retainer between the staples and the pin, said frame being rocked by the closing movement of the closure to move the staple-retainer away from the staples. 10
15. 7. In a stapling or wire-stitching machine, a magazine for holding a supply of staples, a movable closure for the magazine, means for advancing the staples in the magazine, a pin extending transversely of the magazine above the staples, a frame pivotally mounted on the pin, said frame having a cam at one side of the pin and a projection at the opposite side thereof, a wheel on said frame, said wheel having a serrated edge for wedging engagement between the staples and pin, and a spring for rocking the frame to cause the cam to wedge the wheel between the staples and pin, the projection on the frame being engaged by the closure to rock the frame and thereby cam the wheel from wedging engagement with the staples. 15
20. 8. In a stapling or wire-stitching machine, a magazine for holding a supply of staples, a movable closure for the magazine, means for advancing the staples in the magazine, a pin extending transversely of the magazine above the staples, a U-shaped frame pivotally mounted on the pin, said frame having inclined cam-slots at one side of the pin and an abutment at the opposite side of the pin adjacent the closure, a wheel in said frame having a serrated edge and trunnions projecting into the slots, and a spring for rocking the frame to cause the slots to cam the wheel into wedging engagement between the staples and pin when the closure is opened, said abutment on the frame being engaged by the closure when the latter is closed to rock the frame to release the wheel. 20
25. 9. In a device of the type indicated, a magazine for holding a supply of fasteners, a driver for driving the fasteners as they are advanced in the magazine, a pusher of inverted U-shape having a portion of its top wall offset at its forward end to form an ear with the forward edge of the ear inclined rearwardly to provide a cam-face, and resilient means for yieldingly advancing the pusher, said driver being arranged to engage the cam-face on the pusher when the magazine is empty to cam the pusher rearwardly in the magazine. 25
30. 35. JOHN F. CAVANAGH.
